UNITED STATES PATENT OFFICE.

PRESTON K. WOOD, OF LOS ANGELES, CALIFORNIA.

AIR COMPRESSOR.

Application filed June 6, 1925. Serial No. 35,407.

This invention relates to pumps and more especially to rotary air pumps or compressors.

An object is to provide a water cooled rotor and casing in a rotary compressor. Another object is to provide a rotor having side heads forming rotating sides of a piston chamber, and to provide a rotor having independent pistons positively reciprocated.

10 An object is to provide a piston having actuating means and having a yieldingly thrust packer so arranged as to have but small area exposed to fluid pressure reaction.

15 An object is to provide an adjustable gib for take up of wear by the rotor.

Another object is to provide ample lubrication.

20 And an object is to provide annular packing glands and packing for the side heads.

Other objects and advantages will be made manifest in the following specification of an embodiment of the invention; variations, modifications and adaptations being deemed 25 within the scope and spirit of the invention as it is here claimed.

Figure 1 is an axial section of the compressor.

Figure 2 is an elevation and partial section.

Figure 3 is a plan of a piston; broken away.

Figure 4 is a detail of the extended piston.

The form illustrated of the compressor includes a rotor having a pair of positively controlled, radially opposed piston blades with yielding means for maintaining a close fit in a cylinder having inner heads running with the rotor, and which cylinder has outer stationary wells. Means are also included to automatically circulate a cooling fluid through the shell and the rotor.

Means for lubricating the rotor piston blades and also the rotor heads are provided.

45 Further a simple and effective form of annular packing for the running heads is provided.

50 As here shown in Figure 1, a driving shaft 2 is screwed at 3 into one side head or disc 4 which is securely bolted at 5 to a hollow cylindrical rotor 6 having closed sides 7.

On the opposite end of the rotor 6 is bolted a disc head 8 into the outer hub 9 of which is screwed a trunnion 10.

55 The main shaft section 2 runs in a bushing 12 in bearing 13 extending from the cas-

ing end wall 14 which is bolted at 15 to a circular flange 16 of a cylinder 17 having an opposite similar flange 18 bolted to an end wall 19.

The shaft 2-10 is coaxial with the disc heads 4-8 and the walls 14-19 but the cylinder 17 is eccentric to the shaft.

This eccentricity forms a crescent air chamber 20 in which sweep the unconnected 65 piston blades.

The rotor is disposed in close tangency to the top of the cylinder wherein is mortised a take-up gib 21 which may be forced in from time to time by a screw 22.

On one side of the cylinder is an inlet port 23 and opposite is the exhaust port 24, Fig. 2.

The heads 4-8 overlap the rim of the cylinder space 20 and form rotating sides thereof and the bottom of the cylinder has an oil 75 duct 25 leading to the near disc heads.

Just beyond the perimeters of the heads 4-8 there is formed in the flanges and walls, annular run-ways 26-27. In the run-ways 27 are segments of annuli 30 which are mounted on pins 31 in the outer ends of horns 32 which sweep in run-ways 26 and lie in diametrical slots 33 in the inside faces of the disc heads 4-8. The horns which project on one side of the axis of the rotor (which is made a duplicate of semi-cylinders) form a pair to which are secured, rigidly, spaced piston plates 34 which extend laterally into the slots 33 and project out beyond the rotor and nearly engage the concave face of the cylinder 17.

Between the outer portions of each piston is slidable a presser block 35, the outer, transverse edge of which is longitudinally concaved to fit and receive a half-round packing bar 36, which thrusts out against the face of the cylinder.

Between the inner spaced ends of the plates 34 of each piston is secured a bolster 37 and against this rests a set of springs 38 extending into pockets 39 in the block 35 so that the block is yieldingly pressed out against the cylinder face. It will be observed that the exposed area of the pistons takes the reaction pressure of the compressed air but that reciprocation of the pistons is made positive by the coaction of the runners 30 in the eccentric grooves 27. Therefore, only a very small area of the pressure blocks 35 is exposed to pressure as these work in and out during the rotation of the rotor.

In their nearest approach the pistons leave

- a space 40, Fig. 2, and into this flows a lubricant admitted through a hole 41 in bearing 13, thence to a duct 42 in shaft 2 and an aperture 43 in head 4. Lubricant also flows into space 40 through aperture 44 in head 8 and to a duct 45 in the trunnion 10; the outer end of which is covered by a cap 46 which may be provided with a grease cup, on the hub of the end wall 19.
- 10 Bushing 12 is grooved spirally at 12^a to allow lubricant from hole 41 to lubricate shaft 2. The trunnion 10 is lubricated in the same manner from grease cup on cap 46. Holes 67 in cylinder 17 are for grease cups 15 to supply lubricant for the interior of the cylinder, also to lubricate disc heads 4-8 through ducts 68 at a point nearer the center than through oil duct 25.

It will be seen that rotating heads 4-8 20 (of disc wheel form) run snugly against the near end faces of the cylinder 17 and are packed by a film of lubricant from duct 25. To further prevent pressure losses each disc head has a lateral ring 48 of packing which 25 is engaged by a gland band 49 sunk in its respective head 14 or 19, and adjusted inwardly by screws 50.

I provide for water cooling of both case and rotor. This is accomplished by recessing end walls 14-19 at 52 for an area nearly equal to its head 4 or 8. Casing wall 19 has an inlet port 53 and wall 14 has an outlet port 54 near the outer portion of recess 52. The rotor head 8 has, near its center, inlet 35 ports 55 and head 4 has outlet ports 56 leading from the outer portion of the rotor chamber so that centrifugal force will maintain constant flow in and out of the recess 52 and through the rotor. But to enhance this 40 flow I provide centrifugal pumping vanes 58 on the head 4 to run in the recess 52 of wall 14.

Leading away from the gib 21, relief ports 66 are cut in the cylinder wall to the inlet 45 and outlet ports 23-24 to eliminate dead pockets between the air ports.

It will be seen that since the heads 4-8 run with the rotor, only the standing cylinder offers surface resistance to the volume of 50 air swept through.

What is claimed is:

1. A rotary air compressor having a casing forming a fixed cylindrical chamber having side walls recessed to form concentric 55 runways, segmental runners in the runways, a rotor mounted eccentrically in the chamber and having side heads forming running walls and overlapping the stationary ends of the cylinder, and independent pistons mounted for radial movement in the rotor and being connected to the segments so as to be reciprocated thereby.

2. A rotary air compressor having a casing forming a cylindrical chamber having 60 side walls recessed to form eccentric run-

ways, segmental runners in the runways, a rotor mounted eccentrically in the chamber and having side heads forming running walls of the cylinder, and independent pistons mounted for radial movement in the 70 rotor and being connected to the segments so as to be reciprocated thereby, and each piston having a yieldable packing means thrust against the cylinder face, said packing means including a packing bar and a yieldable block in the outer end of which said bar is rollably mounted and has a marginal surface subject to effective pressure on the compression side of the piston.

3. A rotary air compressor having a fixed cylindrical air chamber, inner rotary side heads over-lapping the sides of the fixed chamber and eccentric thereto, a rotor eccentric to the chamber axis and concentric with the side heads and attached thereto, 85 runners in runways in the casing of the chamber, and pistons connected to the runners to be reciprocated thereby and annular packing acting on the sides of the side heads.

4. A rotary air compressor having a cylindrical air chamber, inner rotary side heads over-lapping the sides of the chamber and eccentric thereto, a rotor eccentric to the chamber axis and concentric with the side heads and attached thereto, runners in runways in the casing of the chamber, and pistons connected to the runners to be reciprocated thereby and sliding radially in the side heads and in the rotor.

5. A rotary air compressor having a cylindrical air chamber, inner rotary side heads over-lapping the sides of the chamber and eccentric thereto, a rotor eccentric to the chamber axis and concentric with the side heads and attached thereto, runners in runways in the casing of the chamber, and pistons connected to the runners to be reciprocated thereby; the cylinder casing having outer fixed side walls; the rotor body being hollow, and means for providing for cooling-water circulation through the casing and the rotor cavity.

6. A rotary pump comprising a casing having side walls with recessed inner faces, a shaft device supported in the walls and carrying a rotor which has a diametrical slot from side to side, a cylindrical chamber section secured between the walls and eccentric to the rotor and in tangential contact therewith, end heads connected to the rotor, and pistons sliding in the rotor slot and operatively connected to the fixed cylinder to run in a circle about the shaft.

7. A rotary pump comprising a casing having side walls with grooved inner faces, packing in the grooves, a shaft device supported in the walls and carrying a rotor, a fixed cylindrical chamber section secured between the walls and eccentric to the rotor and in tangential contact therewith; and

5   pistons sliding in the rotor and operatively connected to the fixed cylinder to run in a circle about the shaft; said rotor including disc heads engaging the packing in the side walls and forming sides for the cylinder.

10   8. A rotary pump comprising a casing having side walls with recessed inner faces, a shaft device, supported in the walls, carrying a rotor, a cylindrical chamber section secured between the walls and eccentric to the rotor and in tangential contact therewith; said rotor being hollow and having flow communications with the recesses of the walls for liquid circulation, and pistons sliding in the rotor and operatively connected to the fixed cylinder to run in a circle about the shaft, and pumping vanes carried by the rotor to force cooling circulation in the recesses.

15   9. A rotary air compressor having a rotor with disc heads on its sides, a casing forming an eccentric chamber, side walls having annular ring-glands sunk therein, and packing bands on the heads and opposed to the glands.

20   10. A rotary air compressor having a rotor with disc heads on its sides, a casing forming an eccentric chamber, side walls having annular ring-glands sunk therein, and packing bands on the heads and opposed to the glands; the bands extending into recesses in the side walls.

25   11. A rotary air compressor having a cylinder, rotary side heads overlapping the cylinder ends and being eccentric thereto,

concentric runways around the cylinder ends, casing end walls having annular recesses registering with the grooves; said heads having diametrical grooves, a rotor fixed between the heads and tangent to the cylinder, and pistons working in the rotor and extending into the head grooves and having runners in the runways.

30   12. An air compressor having a rotor with disc heads on its sides, a casing forming an eccentric fluid chamber, side walls fixed to the casing and covering the disc heads, and annular packing means between the side walls and the sides of the heads.

35   13. A pump having an outer cylinder, an inner, cylindrical, piston carrier of equal width with the outer cylinder and tangent thereto, side heads fixed to the inner carrier and overlapping the ends of the outer cylinder, respective supporting means for the cylinder and the carrier and providing for relative rotation, and independent pistons mounted for reciprocation in the carrier and movably connected to the outer cylinder.

40   14. In a pump, an outer member having a cylindrical bore fluid chamber, a radially disposed piston device, and a cylindrical carrier in and tangent to the chamber and in which the piston device is radially movable; said device being connected to the chamber for circular orbital movement and having a packing means yieldingly thrust against the bore face.
